(57) **CLAIM**

The ornamental design for a projectile, as shown and described.

DESCRIPTION

FIG. 1 is a perspective view of the projectile; FIG. 2 is a front elevation view thereof, which is the same as the rear elevation view, top plan view, and bottom plan view;

FIG. 3 is a left elevation view thereof;

FIG. 4 is a right perspective view thereof; and,

FIG. 5 is a right elevation view thereof.

The broken lines showing portions of a projectile are provided for the purpose of illustrating environment that forms no part of the claimed design.
